(57) **CLAIM**

The ornamental design for a shoulder wrap for maintaining electrodes adjacent shoulder for physical therapy, as shown and described.

DESCRIPTION

FIG. 1 is a perspective view of a first embodiment of a shoulder wrap for maintaining electrodes adjacent shoulder for physical therapy;

FIG. 2 is a front view of the shoulder wrap of FIG. 1;

FIG. 3 is a top end view of the shoulder wrap of FIG. 1;

FIG. 4 is a right side view of the shoulder wrap of FIG. 1;

FIG. 5 is a rear view of the shoulder wrap of FIG. 1;

FIG. 6 is bottom end view of the shoulder wrap of FIG. 1;

FIG. 7 is a left side view of the shoulder wrap of FIG. 1;

FIG. 8 is a perspective view of the shoulder wrap of FIG. 1, shown in condition of use;

FIG. 9 is a front view of a second embodiment of a shoulder wrap for maintaining electrodes adjacent shoulder for physical therapy;

FIG. 10 is a top view of the shoulder wrap of FIG. 9;

FIG. 11 is a right side view of the shoulder wrap of FIG. 9;

FIG. 12 is a rear view of the shoulder wrap of FIG. 9;

FIG. 13 is a bottom view of the shoulder wrap of FIG. 9; and, FIG. 14 is a left side view of the shoulder wrap of FIG. 9.

The broken lines illustrate environmental structure and portions of the shoulder wrap which form no part of the claimed design.
